UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

PNEUMATIC CHARGING DEVICE.

Application filed October 14, 1927. Serial No. 226,110.

This invention relates to charging devices, but more particularly to a pneumatic charging device adapted for depositing an explosive in a submerged drill hole.

5 It is an object of the invention to enable an explosive to be suitably deposited and compressed in the bottom of a submerged drill hole.

Other objects will be in part obvious and 10 in part pointed out hereinafter.

The invention consists of the combination of elements and arrangement of parts having the general mode of operation substantially as hereinafter described and claimed and illustrated in the accompanying drawing which is a sectional elevation of a pneumatic charging device constructed in accordance with the practice of the invention.

Referring more particularly to the drawing, A designates a cylinder and B a head threaded into the uppermost end of the cylinder A. The cylinder A is provided at its front end with internal threads C to receive a threaded connection D which supports at its front end a tube E forming an extension of the cylinder and of such external diameter as to enable the said tube to readily enter a drill hole F in the earth formation G and submerged under water H. 25 The interior of the tube E forms a chamber J into which an explosive K may be inserted and suitably maintained for depositing same in the bottom of the drill hole F.

Disposed within the cylinder A is a piston 30 generally designated by L. The piston L is threaded to a hollow rod O and comprises cylindrical block P screwed on the front end of the rod O and a plate Q threaded on a threaded portion R of the rod O located 35 slightly rearwardly of the end of the rod O. Between the block P and the plate Q is disposed a packing, such as a cup leather S, which is held against the wall of the cylinder A by a washer T located in the cup leather S.

To the front end of the block P is threaded a rod U which extends slidably through the connection D. The rod U carries at its front end a lateral flange V to which is secured a non-metallic plunger W by means of screws X. In the retracted position of the piston L, the plunger W may occupy a position in the chamber J adjacent the connection D, thus forming an abutment for 50 the explosive K during the operation of

conveying the device, together with the explosive, to the drill hole F.

On the rearward end of the head B is threaded a connection Y having internal threads Z in its rearward end to receive the 60 threaded end of a stem b. The stem b may be of sufficient length to extend well above the surface of the water H. On the rearward end of the stem b is threaded a sleeve 65 which acts as a guide for the rod O.

Attached to the sleeve c is a link d to which may be tied one end of an ignition wire e, the other end of which carries the detonator f. The wire e may be wrapped or tied around the explosive K to retain the 70 explosive in the chamber J during the transportation of the device to the drill hole. Preferably a slot g is formed in the side of the tube E for the accommodation of the wire e.

In order to lock the piston L, as well as the plunger W, in retracted position after the explosive K has been inserted in the chamber J, a collar h is fitted on the rod O and carries a set screw j whereby said collar 80 may be clamped securely to the rod O.

The rod O may be of any suitable length and carries at its uppermost end a connection k to which is connected a hose line o for conveying pressure fluid from a source of 85 supply (not shown) to a passage p extending throughout the length of the rod O and communicating with the cylinder A through a port q in the rod O. In order to enable the hose line o to be detached from the connection k, a coupling r of any well known type 90 may be interposed between the connection k and the hose line o.

The mode of operation of the device is as follows: After the explosive material, together with the detonator and wire have been inserted into the chamber J, the device may be lowered into the drill hole F so that the forward or open end of the tube E rests on the bottom of the drill hole F. Pressure 95 fluid may then be admitted into the passage p of the rod O and such pressure fluid flowing through the ports q into the cylinder A will force the piston L, together with the plunger W, downwardly to compress the explosive K in the tube E. Only a light pressure will be necessary on the cylinder of the piston to effect such compression of the explosive and during this step in the charging of the drill hole, the weight of the de- 100 105 110

vice will offer sufficient resistance to the pressure fluid to prevent raising of the cylinder and consequently the premature expulsion of the explosive from the end of the tube. However, upon the continued admission of pressure fluid into the cylinder A, the device will, of course, be raised. Such raising of the cylinder however should take place slowly and may be controlled by the operator by bearing on the stem b so that the cylinder will only raise in proportion to the degree in which the explosive may be deposited in the bottom of the drill hole.

After the plunger W has been forced downwardly, a sufficient distance to remove all the explosive from the tube E, a wire e may be detached from the link d and secured to the battery or other means used for exploding the charge. The device may then be removed for refilling. To add additional explosive to the same drill hole in cases where additional charges are required a cord may be substituted for the wire e, or if desired, a wedge may be inserted in the end of the tube e to maintain the explosive within the tube while the device is being transported and inserted in the drill hole F.

After the charge of explosive has been

expelled from the tube, the coupling r may be disconnected, whereupon the pressure fluid utilized for compressing the explosive will be exhausted to the atmosphere. The piston L may then be retracted in the cylinder and the set screw j again turned to lock the collar h on the rod O. In this way the piston, as well as the plunger, may be maintained in retracted position in readiness for a succeeding charge.

I claim:

A pneumatic charging device, comprising a cylinder; a piston reciprocable therein; a plunger, a tube at one end of the cylinder adapted to be inserted into a drill hole and forming a chamber for conveying an explosive into the drill hole, a hollow rod connecting the plunger and the piston to transmit the movement of the piston to the plunger for expelling such explosive from the tube and compressing it in the drill hole, said rod having a port for admitting pressure fluid from the rod into the cylinder, and means connecting the rod with a pressure fluid supply.

In testimony whereof I have signed this specification.

CHARLES C. HANSEN.
